UNITED STATES PATENT OFFICE

PHILIP CARLSON, OF LONG HILL, CONNECTICUT, ASSIGNOR, BY MESNE ASSIGNMENTS,
TO THOMAS RATCHELOUS, OF NEW YORK, N. Y.

DESIGN FOR A TRUCK CAB

Application filed March 5, 1931. Serial No. 38,931. Term of patent 7 years.

To all whom it may concern:

Be it known that I, PHILIP CARLSON, a citizen of the United States, residing in Long Hill, in the county of Fairfield and State of Connecticut, have invented a new, original, and ornamental Design for Truck Cab, of which the following is a specification, reference being had to the accompanying drawings forming a part thereof.

Figure 1 is a side elevational view of the truck cab of the present invention;

Fig. 2 is a front elevational view thereof; Fig. 3 is a rear elevational view of the same; and

Fig. 4 is a top plan view of the top portion of the truck cab.

I claim:

The ornamental design for a truck cab, substantially as shown.

PHILIP CARLSON.
